UNITED STATES PATENT OFFICE.

YOUNG HO KOUN, OF NEW YORK, N. Y.

BUOYANCY UNIT FOR AEROPLANES.

Application filed January 26, 1926. Serial No. 83,829.

The main object of this invention is to provide means for rendering an aeroplane buoyant when it can be in no other way controlled. The means comprises a plurality of 5 silk bags which are mounted upon the wing surface of an aeroplane and are adapted to be filled with hydrogen gas thru a novel type of valve, which when operated, controls the circulation of the gas thru these bags.

10 Another object is to provide a buoyancy unit for aeroplanes having a plurality of silken bags which communicates with a hydrogen tank, the communicating pipe between the hydrogen tanks being equipped 15 with valves which are operated by a novel type of mechanism.

The above and other objects will become apparent in the description below, in which characters of reference refer to like-named 20 parts in the drawing.

Referring briefly to the drawing, Figure 1 illustrates a top plan view of the front portion of an aeroplane, showing the buoyancy unit mounted on one of the plane surfaces.

Figure 2 is a side elevational view of the buoyancy unit, showing the relation of the valve operating means to the remainder of the device.

30 Figure 3 is a longitudinal sectional elevational view of the valve operating means.

Figure 4 is a side elevational view of Figure 3.

Figure 5 is a longitudinal sectional elevational view, showing the valve construction.

Referring in detail to the drawing, the numeral 10 indicates the upper wing of an aeroplane. From this upper wing, a fuselage is usually suspended. The cowl at the front of the fuselage covers the motor which rotates a propeller 12. The buoyancy unit may be mounted upon either plane surface and consists of a plurality of circular bags 13. These bags can be made of such dimensions as will provide a volume suitable for buoying the weight of the craft to which the bags are attached. In the drawing, the buoyancy unit is provided with eight bags, each pair of bags being joined in series and communicate thru a pipe 15 with a hydrogen tank 16 which is located on the side of the fuselage. At a point in the fuselage above the level of the pipes 15, a hollow casing 17 is fixed. This casing has recessed portions 18 at its lower end and into these recesses, the ends of pivoted plates 19 are

inserted. The plates 19 are mounted upon hinges 20 and at their outer free ends have eyelets 21 to which wires 22 are attached. A plunger 23 is slidable vertically in the casing 17 and has a handle 24 at its upper projecting end. This plunger is provided with a collar 25 within the casing and forms a shoulder for a spring 26 coiled about the plunger and retained on the latter by a stationary or fixed flange 27 upon which the spring is seated. This spring is normally adapted to lift the plunger upwardly so that the lower end 28 of the latter permits the plates 19 to normally rest in a horizontal position as indicated in Figure 3.

Each one of the pipes 15 is provided with a valve illustrated in Figure 5. This valve comprises a circular wall 29 formed within the cross section of the pipe. The wall has a pair of aligned openings 30. Within the chamber formed by the wall 29, a piston 31 is slidable. The latter normally takes up half the volume of the chamber within the wall 29 and is normally lifted upwardly by a spring 32 which rests on a threaded cap 33, the cap being provided to permit access to the chamber bounded by the wall 29. The piston has a diametrically extending opening 34 passing therethru which normally rests above the openings 30 when the piston is in lifted position, as shown in Figure 5. A stud 35 projects from the piston thru an opening in the wall of the pipe 15 and is adapted to be engaged by one end 36 of the lever 37. This lever is pivotally mounted at a position intermediate its length on a pin 38 supported on lugs 39. The opposite end of the lever has an upwardly extending ear 40 thereon in which an opening is provided, the opening being formed to permit the wires 22 to be secured to the levers.

The device is adapted to be used as a buoyancy agent when an aeroplane or heavier than air craft becomes unmanageable. As an aeroplane is lost control of, the handle 24 is depressed pivotally and as the lower end 28 of the plunger 23 contacts with the inner ends of the plates 19, the latter have their outer ends lifted. The eyelets 21 at the outer ends of the plates have the wires 22 secured thereto and as these wires are connected at their lower ends to the ears 40 of the levers 37, said levers are rotated. The levers being in contact with the members 35 of the valve pistons 31, depress the latter against the tension of the springs

32 to a position where the diametrically extending opening 34 in the piston registers with the openings 30 in the wall 29 and permits hydrogen gas with which the tanks are 5 filled to flow from the tanks thru the pipes 15 and into the bags 13 which then become buoyant and aid in keeping the aeroplane in a floating condition so that the same may drift to earth slowly.

10 I claim:—

1. In an aeroplane, a buoyancy unit comprising bags adapted to be mounted on the wings, hydrogen tanks communicating with said bags thru pipes, said tanks being normally filled with hydrogen, pipes mounted and connecting the bags and tanks, valves mounted in said pipes comprising lever operated pistons normally closing communication between the bags and tanks, means beneath said pistons for closing communication between the bags and tanks, pivoted levers cooperating with said pistons for depressing the latter, means for rotating said levers comprising a plunger, a casing receiving said plunger, plates adapted to be rotated, said plates being connected to said levers.

2. In an aeroplane, a buoyancy unit comprising bags adapted to be mounted on the wings, hydrogen tanks communicating with said bags thru pipes, said tanks being normally filled with hydrogen, pipes mounted and connecting the bags and tanks, valves mounted in said pipes comprising lever

operated pistons normally closing communication between the bags and tanks, means beneath said pistons for closing communication between the bags and tanks, pivoted levers cooperating with said pistons for depressing the latter, means for rotating said levers comprising a plunger, a casing receiving said plunger, plates adapted to be rotated, said plates being connected to said levers, hinges connecting said plates to the casing, said plates extending outwardly in opposite directions, and a spring mounted on said plunger being adapted to lift the latter and permit horizontal alignment of the hinge plates when said valve pistons are in closed position.

3. In an aeroplane, a buoyancy unit comprising circular bags, hydrogen tanks coupled to said bags, pipes connecting said tanks and bags, valves mounted in said pipes comprising a lever pivoted intermediate its length on said pipe, pistons slideable in said pipe adapted to close communication between the bags and tanks, means for rotating said levers comprising a vertical slideable plunger, a cylinder in said casing slideably receiving said plunger, hinged plates having one of their ends projecting beneath said plunger, said plates being pivotally secured to said casing, and means for connecting said levers to said plates.

In testimony whereof I affix my signature.

YOUNG HO KOUN.
